**DEVICE FOR EXHAUSTING BROKEN THREADS
IN SPINNING MACHINES**

Joachim Fürsteberg, Esslingen (Neckar), Germany, assignor to Pneumafl Corporation, Charlotte, N. C., a corporation of Delaware

Application July 10, 1951, Serial No. 235,967

16 Claims. (Cl. 57—34.5)

This invention relates to devices for exhausting broken threads in spinning machines. Devices for exhausting broken threads in spinning machines are generally well known today. They can also be utilized, without substantial alteration, for fly-frames.

In principle, two main requirements are imposed in the exhausting of broken threads, on the way in which the air current is caused to act:

(1) The catching and exhausting of a broken thread in any position occurring during the change motion along the drawing frame;

(2) The freeing of the lower delivery roller of the drawing frame from dust and loose fibres.

By reason of its comparatively greater volume, the exhausting of a thread is easier to achieve than the exhausting of individual loose fibres which, in addition, tend to adhere more firmly to the fluted roller of the drawing frame. The suction effect must, therefore, not only be sufficiently strong and extend over the entire change motion necessitating by the guiding of the yarn but, especially in view of the last mentioned requirement, it must also bring about an optimum air circulation round the fluted roller.

A further problem in this connection resides in the fact that in the event of broken threads, which occur between the guide eyelet and the ring rail, the thread often becomes twisted in the guide eyelet as the result of the twist imparted to it.

In that case, by means of a properly arranged thread exhausting device, the thread will, it is true, be caught up between the drawing frame and the guide eyelet and the yarn subsequently delivered by the drawing frame continue to be delivered; when the broken thread becomes twisted in the guide eyelet, however, an end of yarn frequently hangs between the eyelet and the nozzle and extends into the latter and in the nozzles of the existing type the continued delivery from the drawing frame may lead to the exhaust tube becoming choked by fibres.

In order to allow for all the above-mentioned problems and thus eliminate the existing difficulties, according to the invention the nozzle outlet of such exhaust tubes exhibits, at least substantially, the basic shape of a triangle which theoretical considerations and practical tests have shown to be the most advantageous.

At the same time, in utilizing the triangular cross section, it is particularly advantageous to select an isosceles triangle, the apex of which is turned towards the drawing frame roller which primarily most often needs to be cleaned, that is to say towards the fluted roller. It is also advisable slightly to round off the corners of such a nozzle outlet.

Moreover, it is also possible, within the scope of the invention, likewise to promote the suction air circulation round the pressure roller located above the fluted roller of the drawing frame, if, depending upon the position of the said roller relatively to the fluted roller, the nozzle is arranged obliquely to the longitudinal axis of the nozzle

2

tube. Finally, the nozzle can be brought as close as possible to the fluted roller and hence also to the bite or nip formed between fluted roller and pressure roller, by providing a suitable recess in the nozzle tube adjacent to the nozzle outlet and on the side of its peripheral curvature nearest to the fluted roller.

The accompanying drawing shows on the one hand, a number of known nozzles with their corresponding conditions of flow and, on the other hand, a number of embodiments of the nozzles, exhaust tubes and suction heads, designed in accordance with the invention, together with the relevant parts of a spinning machine.

Figure 1 is a diagrammatic view of a known type of nozzle outlet with the corresponding distribution of the lines of flow;

Figure 2 is a diagrammatic view of the type of nozzle shown in Figure 1 with the corresponding lines of constant suction strength in their position relatively to the fluted roller;

Figure 3 is a diagrammatic view of another type of nozzle outlet with the corresponding distribution of the lines of flow;

Figure 4 is a diagrammatic view of the nozzle shown in Figure 3 with the corresponding lines of constant suction strength in their position relatively to the fluted roller;

Figure 5 is a diagrammatic view of another type of nozzle outlet with the corresponding distribution of the lines of flow;

Figure 6 is a diagrammatic view of the nozzle shown in Figure 5 with the corresponding lines of constant suction strength in their position relatively to the fluted roller;

Figure 7 is a diagrammatic view of the nozzle aperture provided by the present invention with the corresponding distribution of the lines of flow;

Figure 8 is a diagrammatic view of the nozzle aperture shown in Figure 7 with the corresponding lines of constant suction strength in their position relatively to the fluted roller;

Figure 9 is a diagrammatic view of a modified form of the nozzle aperture;

Figure 10 is a diagrammatic view of a modified embodiment of the nozzle aperture;

Figure 11 is a diagrammatic view of another modified form of the nozzle aperture;

Figure 12 is a view in side elevation of a drawing frame having individual exhaust tubes for the broken threads, such tubes being provided with the apertures of the present invention;

Figure 13 is a view in front elevation of the frame shown in Figure 12;

Figure 14 is a view in side elevation of a frame provided with an exhausting device, having a suction head and manifold;

Figure 15 is a view in front elevation of the device shown in Figure 14.

Figure 16 is a diagrammatic view of the exhaust tube and nozzle outlet in their position relatively to the fluted roller and pressure roller of a drawing frame;

Figure 17 is a view in side elevation of a modified suction head;

Figure 18 is a view partly in elevation and partly in section of the suction head shown in Figure 17;

Figure 19 is a sectional view through a nozzle tube; and

Figure 20 is a sectional view through an exhaust tube provided with a fitted-on outlet.

As shown in Figs. 1-6, the nozzle tubes of a thread exhausting device in spinning machines were hitherto normally provided with a nozzle outlet of round or rectangular cross section 2, 3, 4, the latter being arranged with their longitudinal axis either transversely or parallel

to the fluted roller (1) of a drawing frame. The way in which the conditions of flow and the direction and density of the threads 6 as well as the lines 7 of equal suction strength around the nozzles are distributed will be seen in Figs. 1-6 in comparison with corresponding arrangements shown in Figs. 7 and 8 for the new triangular form 5 of an exhaust nozzle. At the same time Figs. 2, 4, 6 and 8 show how the exhausting range of the particular type of nozzle and arrangement lie in relation to the fluted roller. It will at once be apparent that a triangular nozzle according to Figs. 7 and 8 has the best and the most uniform effect over the entire change width of B of the fluted roller 1 determined by the movements of the threads.

Within the scope of the basic triangular form of the nozzle outlet according to the invention and whilst allowing for the particular conditions involved, special embodiments are possible as shown by way of example in Figs. 9-11. Some or all of the sides forming the triangle may be rectilinear or, as shown by Figs. 9-11, some or all of the lines may be curved or deflected slightly inwards or outwards.

According to the experience so far gained an isosceles triangle having its apex turned towards the lower delivery roller of the drawing frame and rounded corner of the nozzle outlet, has proved particularly advantageous.

The said shape and arrangement is shown in Figs. 12 and 13 by way of example in an exhausting device in which each thread leaving the drawing frame, shown by the pair of rollers 11, 12 and 9, 10 and the conveyor leathers 13, is provided with a separate suction tube 14 which is connected in the known manner with the central duct or flue 15. The nozzle outlet of the suction tube 14 is located below the fluted roller 9 and is so arranged that the pressure roller 10 located obliquely above it is also within the range of the air circulation.

In the embodiment shown in Fig. 16, the suction tube 16 carrying the nozzle outlet according to the invention is provided with a recess 16' adapted to fit the peripheral curvature of the fluted roller 18. In consequence it is possible to arrange the nozzle outlet particularly close to the bite or nip formed between the fluted roller 18 and the pressure roller 19. The yarn 17 leaving the drawing frame is guided in known manner past the nozzle outlet of the suction tube 16 and through the guide eyelet 20. According to the construction of the spinning machine, the same purpose can be achieved by suitably bending the entire tube.

The same figure also shows obliquity at the angle shown in the drawing, of the plane of the outlet relatively to the longitudinal axis of the suction tube. All these measures contribute to improving the exhausting action within the range of a broken thread and also to a more advantageous air circulation round the drawing frame rollers.

The embodiment according to Figs. 14 and 15 differs from those described above by the fact that in this case, an exhaust manifold 21 of known T or L shape is provided, which leads to a central duct 23 and the suction head 21' of which consists of a tube arranged parallel to the drawing frame rollers. The said tube is shown here with a circular cross section but it may equally well be given any other suitable shape. In any case it is provided at suitable points for catching up and exhausting the broken threads, with nozzle apertures 27 of the basic triangular shape according to the invention. The drawing frame is represented in this instance by the pairs of rollers 25, 26 and 28, 29 through which the yarn 24 passes.

Particularly in those cases in which the clearing roller for the fluted roller is to be retained, it is expedient to resort to a different design, of the above-mentioned suction heads. This is shown in Figs. 17 and 18. In this case the nozzle outlets are not fitted in the head 30 itself; on the contrary the latter carries a plurality of short suc-

tion sockets 31 the nozzle outlet of which again exhibits the basic triangular shape according to the invention. The length, number and position of these suction sockets depends upon the details of the spinning machine, of which the drawing shows the pair of delivery rollers 33, 34 through which the yarn 32 passes, as well as the clearer 35 for the fluted roller. The suction head 30 is connected, through the connecting tube 36, in known manner with the central duct 37. The suction sockets 31 may be made interchangeable to enable them to be adapted to different grades of yarn. Moreover, these suction sockets may be given a special internal shape as will be explained later and it may be expedient in the case of a suction head having four or more suction points, to design the suction sockets farthest away from the connecting tube 36 with an appropriate internal profile so as to ensure that a constant quantity of air is exhausted at each suction point.

For reasons connected with manufacture and ease of flow, it is generally preferable to impart a circular shape to the suction tubes 14 and 16. The transition from the triangular nozzle outlet to the round part of the tube is by no means a matter of indifference. The shape of this transition point evolved in accordance with the invention will be briefly explained with the aid of Fig. 19. The inflow edges and the round corners *a* of the nozzle outlet on the suction tube 40 are rounded outwards. This rounded portion is followed by a uniform relatively rapid transition of the nozzle aperture to the round cross-section, the latter, however, being slightly smaller at *b* than the total cross section of the nozzle aperture proper at *a*. The narrowest point thus formed is followed, whilst retaining the round cross section, in continuous transition by an expansion until the normal internal diameter of the suction tube is reached at *c*.

This profile can be imparted to the suction tube itself or, as shown in Figure 20, to a special mouthpiece 39 fitted on the suction tube 38. This mouthpiece 39 is fitted over the suction tube. By interchanging it the suction tube can be adapted to suit different requirements. A suitably shaped mouthpiece 39 can, however, also be inserted either wholly or in part in the suction tube 38. The suction sockets 31 illustrated in Fig. 18 can also be shaped to advantage in accordance with the foregoing description.

By altering the shape of the mouthpiece 39 and in particular, as shown at *d*, by making more or less deep borings along the dotted line (shown in Figure 20) but not as far as the narrowest portion *b*, it is possible to ensure, that the same quantities of air flow through the nozzle aperture, in spite of variations in the pressure. In this way it is possible to ensure that the suction effect of the broken thread exhausting device is equal both in the case of the first and the last spindles of a spinning machine, even if local differences in pressure exist in the central duct which traverses the entire spinning machine and to which the individual mouthpieces through the small tubes or the suction heads are connected.

The above mentioned suction tubes and mouthpieces may be made of any desired material, for example, from cast or pressed metal or from a colored or transparent plastic material. They are suitable both for stationary suction tubes and suction heads as well as for those adapted to move up and down or backwards and forwards as a function of the progress of the thread. On account of their widthwise spread they may also be fitted with particular advantage in appropriate orifices or slots in clearing rollers.

I claim:

1. In an exhausting device for collecting lint and broken ends for use with spinning frames and fly-frames having rollers, the combination of a suction head arranged adjacent the rollers and parallel to the axis of the frame, said suction head having at least one aperture arranged opposite to a thread leaving the frame, the aperture exhibit-

ing the basic shape of a triangle having the apex adjacent the rollers thereby ensuring the optimum effect in breadth in regard to suction strength and air circulation round the frame rollers.

2. In an exhausting device for collecting lint and broken ends for use with spinning frames and fly-frames having delivery rollers, the combination of a plurality of suction tubes placed adjacent delivery rollers of the frame, each suction tube having a nozzle aperture exhibiting the basic shape of a triangle having the apex adjacent the rollers thereby ensuring the optimum effect in breadth in regard to suction strength and air circulation round the frame rollers, the nozzle aperture in each suction tube being at the end thereof arranged opposite to a thread leaving the frame.

3. An exhausting device according to claim 2 in which the nozzle aperture has inflow edges and rounded corners.

4. An exhausting device according to claim 2 in which the triangular cross section of the nozzle aperture merges inside the suction tube and in the direction of the flow of air into a round cross section of the suction tube which is smaller than the cross section of the nozzle aperture, the suction tube increasing in internal diameter in the direction of air flow from the round cross section until it reaches the normal internal diameter of the suction tube.

5. An exhausting device according to claim 4 in which the suction nozzles arranged on one side of a frame are adjusted to a uniform suction effect at the triangular nozzle apertures by each suction tube having its zone of transition of a size to permit the same suction in each tube.

6. An exhausting device according to claim 2 in which the nozzle aperture is placed obliquely to the longitudinal axis of the suction tube.

7. An exhausting device according to claim 2 in which the suction tube is provided adjacent the nozzle aperture with a recess in its side turned toward the delivery roller of the frame.

8. An exhausting device according to claim 2 in which the suction nozzle aperture of the suction tube has two sides converging toward the lower delivery roller of the frame.

9. In combination with a spinning frame having delivery rollers, an exhaust device for collecting lint and broken ends, said exhaust device including means placed adjacent the delivery rollers of the frame, an exhausting member, said means being connected to the exhausting member and at least one suction nozzle in said means having an aperture adjacent the delivery rollers of the frame which exhibits the basic shape of a triangle having the apex adjacent the rollers thereby ensuring the optimum effect in breadth in regard to suction strength and air circulation round the frame rollers.

10. The combination, according to claim 9, in which the apex of the triangle is turned toward the lower delivery roller of the frame.

11. The combination, according to claim 9, in which the nozzle aperture has inflow edges and rounded corners.

12. The combination, according to claim 9, in which

the triangular cross section of the nozzle aperture merges inside said means and in the direction of the flow of air into a round cross section, said round cross section being smaller than the cross section of the nozzle aperture, the diameter of said means increasing from said round cross section in the direction of air flow until it reaches a desired internal diameter of said means.

13. The combination, according to claim 12, in which the variations in the internal profile of the nozzle are incorporated in a removable mouthpiece.

14. A nozzle for an exhausting device for collecting lint and broken ends for use with spinning frames and fly frames having delivery rollers having an aperture having corners and inflow edges, adapted to be placed adjacent the delivery rollers, said aperture having the shape of a triangle to ensure the optimum effect in breadth in regard to suction strength and air circulation round the frame rollers, the corners and inflow edges of the aperture being rounded.

15. A nozzle, according to claim 14, in which the triangular cross section of the aperture merges inside the nozzle and in the direction of the flow of air into a round cross section, said round cross section being smaller than the cross section of the nozzle aperture, said round cross section increasing in diameter in the direction of the flow of air until it reaches the desired internal diameter of the suction tube.

16. In an exhausting device for collecting lint and broken ends for use with spinning and fly frames having delivery rollers, the combination of a plurality of suction tubes placed adjacent delivery rollers of the frame, each suction tube having a removable mouthpiece attached thereto, each mouthpiece having an aperture exhibiting the basic shape of a triangle having the apex adjacent the rollers thereby ensuring the optimum effect in breadth in regard to suction strength and air circulation round the frame rollers, the aperture in each mouthpiece being at the end thereof arranged opposite to a thread leaving the frame, the triangular cross section of the mouthpiece aperture merging inside the mouthpiece

30 and in the direction of the flow of air into a round cross section of the mouthpiece which is smaller than the cross section of the aperture, the mouthpiece increasing in internal diameter in the direction of air flow from the round cross section until it reaches the normal internal diameter of the mouthpiece, the mouthpieces of suction tubes arranged on one side of a frame being adjusted to a uniform suction effect at the triangular apertures by each mouthpiece having its zone of transition from the narrowest cross section to the normal internal diameter shortened corresponding to the differences in pressure.
